UNITED STATES PATENT OFFICE

CARL OTTO WANNACK, OF CHICAGO, ILLINOIS, ASSIGNOR, BY MESNE ASSIGNMENTS, TO
S. H. G. INCORPORATED, OF CHICAGO, ILLINOIS, A CORPORATION OF DELAWARE

PROCESS FOR MAKING CARBURETED AIR GAS

Application filed June 14, 1928. Serial No. 235,229.

My invention relates to a process for making carbureted air combustible gas, and refers more particularly to the production of a stable uniform B. t. u. content gas from a combustible liquid such as a hydrocarbon liquid, and more specifically such as gasoline or the like by breaking up and bringing air and hydrocarbon liquid into intimate relation with each other whereby a dry stable uniform B. t. u. content gas is formed.

An object of my invention is to supply a great demand for a self-contained automatic gas generating process which provides a complete plant for installation in districts remote from and/or not supplied with natural or manufactured gas from a central gas station, particularly for domestic use, for stoves, house heating, and the like. In its broader aspects, of course, it is to be understood that the process of the present invention is equally applicable to the largest industrial uses as well as the smallest domestic uses.

Another and further object of my invention is the provision of a method for making a combustible gas from liquid hydrocarbon which is simple in operation, effective in service, and safe for use without the danger of explosion resulting from flash backs from the burner or combustion from other accidental causes.

Another and further object of my invention is to provide a process capable of producing a stable uniform B. t. u. content gas.

Various attempts have been made to supply the demand for a self-contained automatic gas generating process by apparatus where air is passed through gasoline or like combustible material, and in passing therethrough the air converts or picks up some of the hydrocarbon in the shape of vapors, thus forming a carbureted air gas. The processes of the prior art have not proved entirely satisfactory for the reason that gasoline-like hydrocarbons are a mixture of hydrocarbons having a wide range of boiling points, and in the passage of air through such gasoline-like hydrocarbons to make gas, the air invariably picks up the lighter ends of the gasoline-like hydrocarbon with the result that eventually

a residue of the higher boiling point portions thereof is left.

Gas made in the above manner gradually becomes poorer in quality and finally so poor, because of the volume of air to gasoline-like vapor being so great, that it will no longer burn.

Further, during the period from the production of the best gas to the production of the poorer gas, the quality of the gas is changing; hence, said air mixture at the burner is not suitable for this range of difference in the richness or leanness of the gasoline vapors in the mixture.

By actual trial I have succeeded in making a uniform mixture of carbureted air gas by forcing air and combustible hydrocarbon through a non-absorbent substance, functioning to minutely divide the air and hydrocarbon into finely divided condition and thoroughly and intimately mix the two to produce a stable gas of a uniform quality. The process is so carried out that the air will not rob the gasoline-like hydrocarbon of its lighter ends. In other words, the gas produced by the present invention is substantially uniform for all practical purposes during the entire consumption of the combustible hydrocarbon.

As a feature of the present invention, the air and hydrocarbon are brought into intimate contact in such a manner that the gas is formed without disturbing or agitating the entire body of the liquid hydrocarbon, so that the disadvantages of washing the newly formed gas through a body of liquid hydrocarbon are eliminated. As an additional feature of the process, the air is introduced in such a manner that a portion of it is used solely as a diluent for the gas formed from the contact between the balance of the air and the combustible liquid.

The utility of the invention as well as other objects and advantages will be more fully and better understood from the following specification.

In the drawings, Fig. 1 is an elevational view, partly in vertical section, illustrating the installation of equipment for practicing the present process.

Fig. 2 is an enlarged fragmentary vertical sectional view of the gas producer.

Fig. 3 is a vertical sectional view taken on line 3—3 of Fig. 2.

5 Fig. 4 is an enlarged fragmentary vertical sectional view illustrating the connection between the stationary and movable elements.

Fig. 5 is a bottom plan view of the bottom closure cap illustrated in Fig. 4.

10 Fig. 6 is a cross sectional view on line 6—6 of Fig. 2.

Before entering into a detailed description of the drawings, it may be well to briefly describe the process.

15 Air is forced in the usual manner by a blower through a stationary pipe connected to a tank holding a bulk supply of liquid hydrocarbon, and cooperatively associated with this stationary pipe entering inside of

20 this tank to a depth, prearranged from the bottom of said tank, is a tubular column filled with suitable non-absorbent material, which column is supported by a suitable float, enabling it to sink into the body of liquid 25 hydrocarbons to a predetermined depth, depending upon the boiling points of said hydrocarbon liquid.

The floating column slides freely vertically on said stationary air supply pipe until it 30 has reached the bottom of said storage tank through the diminishing of said liquid, converting said liquid into a stable uniform B. t. u. content gas without disturbing or 35 agitating the bulk supply of liquid hydrocarbons.

Referring more in detail to the drawings, 1 designates an air inlet pipe communicating with a point exteriorly of the building, designated diagrammatically at 2. Suction is imposed on this pipe 1 by means of a conventional blower 3 operated through the medium of a motor 4, which has electric current connections with an automatic mercoid control, designated diagrammatically at 5, the connecting wires being illustrated at 6. The 45 blower forces air through the pipe 7, in which may be interposed a check valve 8 and an air scrubber 9, into a pipe 10. The air scrubber 9 will mechanically remove moisture contained in the air over and above that amount which may be normally held by the air at a given temperature. Pipe 10 extends into the interior of a tank or container 11 which is used as a storage tank for holding a predetermined supply of combustible liquid 12, such, for instance, as a hydrocarbon liquid, and more specifically gasoline or the like.

The pipe 10 is stationary and non-movable, being welded or otherwise suitably connected 60 to the tank 11 in such a manner that it does not move. Air forced through the pipes 7 and 10 discharges into a chamber 13 formed between the lower end of the pipe 10 and the upper surface of a closure cap 14, closing the 65 bottom of a movable tubular column 15. The

column 15 comprises an annular chamber adapted to be filled with non-absorbing material 16, such, for instance, as steel wool or the like. Connected to the column 15 is a float 17 of a conventional type, the arrangement being such that the float floats in the liquid 12 and as the level of liquid recedes in the tank 11 the float will be carried downwardly, carrying with it the column 15.

Above the closure cap 14 the inner tube of 75 the column 15 may be provided with spaced apertures 18.

The arrangement is such that air discharging from the lower end of the pipe 10 passes through the apertures 18 into the chamber of 80 the column 15 containing the non-absorbent material 16. Due to the pressure of the surrounding liquid, the air will seek the path of least resistance and will ascend through said absorbent material. Liquid from the liquid body 12 will siphon into the chamber holding the non-absorbent material 16 through the medium of the apertures 19, there being at all times a uniform height of liquid in the chamber containing the absorbent material 90 16. Thus, it is obvious that the air discharging through the apertures 18 into the body of absorbent material 16 will be forced to pass upwardly through this body of liquid of predetermined uniform depth, during which 95 time said air will become intimately mixed with said liquid and will carry same upwardly, the non-absorbent material during the ascent of said air-liquid mixture tending to break up the mixture into finely divided 100 gaseous condition, which gas passes out of the upper end of the column 15 through the apertures 20 in the closure cap closing the top of the column, said gas discharging into 105 the vapor space of the chamber 11.

This gas will pass into the conduit 21 positioned inside the chamber 11, but adjacent the upper wall thereof. The conduit 21 may be positioned on an angle from the horizontal, that is, in sloping position with its inlet end disposed lower than its outlet end for the obvious purpose of permitting any liquid trapped in the conduit 21 to flow downwardly by gravity back into the body of liquid hydrocarbon 12. The pipe 21, of course, may be vertical, or it may be horizontally positioned, and it is preferably packed with steel wool or a similar porous mass having a plurality of capillary spaces. As the mixture passes therethrough it is still broken up into finely divided condition, any liquid not thoroughly mixed draining back into the bulk supply 12. The gas then passes through line 23 which has direct communication with the conduit 21.

Returning now to Fig. 2, it is to be noted that the tubular column 15 slides freely on said stationary pipe 10. The distance between pipe 10 and column 15 is preferably carefully worked out beforehand so as to 125 30

5 permit a definite amount of air to be introduced through the pipe 10 to pass upwardly between the walls of pipes 10 and 15 without coming into contact with any part of the liquid hydrocarbon until said air discharges above the upper end of the closure cap 20'. This is of particular importance in the use of the present process, since the passage of this small portion of air into the free space 10 above the liquid body, which is used as gas storage, will help to reduce the B. t. u. content of the gas to the desired point so that the gas made will compare in B. t. u. content with gas with which it may compete. It is 15 to be noted, of course, that the amount of air passing through the telescope section of air supply pipe and floating column is pre-arranged depending upon the boiling points of the liquid used.

20 The carbureted air gas passing through the line 23 may be discharged into the line 24, in which line is interposed the mercoid control 5 heretofore described, the pressure regulating valve 25, valve 26, from which it 25 passes into line 24' and from the latter to a burner or other place of utilization. Interposed in the line 24' may be a safety valve 27 communicating through the medium of the pipe 28 with the atmosphere.

20 For the purpose of safety, the tank 11 may be located beneath the surface of the ground and may be supplied with gasoline or other hydrocarbon to be used through the charging pipe 29.

25 The operation of the process is as follows: The switch 5 is set so that it will operate the pump to maintain a predetermined pressure on the tank 11. When the pressure on tank 11 reaches this predetermined point, it causes the 30 automatic electric switch 5 to disengage, thus temporarily shutting off the motor. When the pressure drops below the predetermined amount because of consumption of gas it causes switch 5 to again make contact to start 35 the motor and place the latter again in operation, it being understood that the only function of the motor 4 is to operate the blower 3 which forces air into the tank 11. It will be readily appreciated that the process is automatically maintained at a predetermined 40 suitable pressure, say 3 lbs. per square inch, more or less. The burners or other consuming devices are shut off and, of course, the automatic electric switch 5 has been disengaged due to the pressure rising to a predetermined 45 point, which interrupts the operation of the motor and air compressor, and everything is in a quiescent state. If gas is wanted, a suitable valve at the burner is opened and 50 this starts the flow of gas from the container 11 through lines 23, 24 and 24' into the burner (not shown), thus causing the pressure to drop.

55 In actual operation good results have been secured by having the automatic switch con-

trol set so that it makes contact to place the blower in operation when the pressure drops below one and one-half pounds and shuts off again when the pressure has been built up to four and one-half pounds per square inch. 70 These figures, of course, are purely illustrative and are not to be taken in any sense as a limitation of the process.

The drop in pressure to the minimum for which the electrical control switch 5 is set 75 causes the latter to engage, which in turn places the motor and air compressor in operation, thus forcing air through stationary pipe 10 into the column 15, causing the air and hydrocarbon to be thoroughly broken up and 80 completely mixed. This mixture is then passed through the conduit 21 where it is freed of any unmixed liquid gasoline, after which the gasoline passes through the lines 23, 24 and 24' to the burners or other consuming devices, which operation continues as 85 long as the gas is being consumed.

As a rule, which is known as casing head gasoline is used in processes of this character, although a heavier gasoline may be used. 90 If a very light casing head gas is used and the gas is too rich, the distance between the pipe 10 and column 15 is increased to permit a greater quantity of air to be passed there- 95 between for diluting purposes. Conversely, if the gas is too lean the distance between the pipe 10 and column 15 is decreased so as to decrease the supply of diluting air.

As a feature of the invention, it is to be noted that the air discharging through the 100 apertures 18 into the column 15 will always pass through a predetermined depth of liquid hydrocarbon, that is, the height of liquid in the base of the column 15 will never be above the liquid level of the bulk supply 12, 105 regardless of whether the tank is almost completely full or almost completely empty, the float, of course, moving upwardly and downwardly with the increase and decrease of liquid level. The tank is never charged with an 110 excess of liquid sufficient to shut off the apertures 18. As an advantage of this feature of passing the air through a predetermined supply of liquid, the air and liquid are brought into intimate contact to form the gas and this 115 gas thereafter is not washed by being forced to pass through the entire body 12.

When the supply of liquid hydrocarbon 12 is converted into a stable gas and the freely sliding floating column 15 has reached the 120 bottom of the tank, sufficient liquid remains in the tank to prevent forming an explosive mixture. Since the air discharging through the ports 18 ascends, and is prevented from descending due to the liquid seal, the ascent 125 of said air will function to siphon the liquid needed into the floating column 15.

Due to the fact that the air only agitates the liquid which is in the column 15, and further because of the fact that this amount is 130

always a definite amount, I produce a constant mixture of uniform B. t. u. gas which cannot be accomplished when the newly formed gas is washed in passing through the large liquid body.

5 By the term "combustible liquid" as used in the specification and claims hereof, I intend to include volatile liquids capable of producing a combustible gas when brought into contact with air under pressure and under controlled conditions, examples of which are pentane, hexane, benzol, alcohols, gasoline, et cetera.

I claim as my invention:

15 1. A process of generating combustible carbureted air gas, which comprises maintaining a bulk supply of volatile combustible liquid under pressure in a closed zone, temporarily isolating a portion of the liquid from said bulk supply, intermittently introducing air under pressure into contact with the isolated liquid to form combustible gas, withdrawing combustible gas thus formed from the gas storage zone thereby reducing the pressure in said storage zone, and automatically regulating the introduction of air to said storage zone by the reduction in pressure following the withdrawal of gas from said storage zone.

30 2. A process of generating combustible carbureted air gas, which comprises maintaining a bulk supply of volatile combustible liquid under pressure in a closed zone, temporarily isolating a portion of the liquid from the said bulk supply, intermittently introducing air under pressure into contact with said isolated portion of the liquid to form combustible gas, confining said gas in a gas storage zone, withdrawing combustible gas from said storage zone, and replenishing the liquid in said isolated portion by causing liquid to flow thereinto from said bulk supply.

35 3. A process of producing combustible carbureted air gas, which comprises maintaining a bulk supply of combustible liquid under pressure in a closed zone temporarily isolating a portion of the liquid from said bulk supply, introducing air under pressure into contact with a portion of said isolated liquid, thereby forming combustible gas, storing said gas in a gas storage zone, withdrawing combustible gas from said storage zone, thereby reducing the pressure therein, intermittently building up the pressure in said storage zone to a predetermined maximum when the withdrawal of gas has reduced the pressure to a predetermined minimum.

40 4. A process of producing combustible carbureted air gas, which comprises maintaining a bulk supply of combustible liquid under pressure in a closed zone temporarily isolating a portion of the liquid from said bulk supply, introducing air under pressure into contact with a portion of said isolated liquid, thereby forming combustible

gas, storing said gas in a gas storage zone, withdrawing combustible gas from said storage zone, thereby reducing the pressure therein, intermittently building up the pressure in said storage zone to a predetermined maximum when the withdrawal of gas has reduced the pressure to a predetermined minimum, and during the step of building up said pressure introducing the air required for the formation of the combustible gas.

45 5. A process of making combustible carbureted air gas, which comprises maintaining a bulk supply of volatile combustible liquid under pressure in a closed zone temporarily isolating a portion of the liquid from said bulk supply, introducing air under pressure into contact with a portion of said isolated liquid, thereby forming combustible gas, storing said gas in a gas storage zone, withdrawing combustible gas from said storage zone, thereby reducing the pressure therein until a predetermined minimum is reached, automatically building up said pressure to a predetermined maximum by the introduction of a fresh supply of air, and maintaining a supply of gas available for consumption by intermittently supplying new charges of air, thus restoring the pressure in the storage zone to a maximum.

In testimony whereof I affix my signature.

CARL OTTO WANNACK.
